Primary Examiner — Jasmine Mlinarcik(74) *Attorney, Agent, or Firm* — Dennen IP Law, LLC(57) **CLAIM**

The ornamental design for a visor, as shown and described.

DESCRIPTION

FIG. 1 is a right, side perspective view of a visor in a position of use;

FIG. 2 is a right, side perspective view thereof;

FIG. 3 is a front view thereof;

FIG. 4 is a left side view thereof;

FIG. 5 is a back view thereof;

FIG. 6 is a right side view thereof;

FIG. 7 is a top plan view thereof; and,

FIG. 8 is a bottom plan view thereof;

The broken-line of the partial human figure assists in illustrating how the claimed design may appear when worn, but forms no part of the claimed invention.

1 Claim, 8 Drawing Sheets(56)
